UNITED STATES PATENT OFFICE

WILLIAM WALTER SIMMONS, SR., OF EVANSVILLE, INDIANA

DISPLAY FIGURE OR STAND

Application filed April 15, 1927. Serial No. 184,159.

The object of the present invention is to provide an improved display stand having the appearance of a human being or of an animal, provided with extremities of grotesque appearance for supporting the goods, for instance men's hosiery, in such fashion that the attention of passers-by will be directed to the stand because of its unusual appearance.

A practical embodiment of the invention 10 comprises the standing or sitting figure of a man, woman, or child whose hands are of greatly increased size and grotesque appearance and serving as a support of the goods to be displayed, or, the stand may assume the 15 outline of an animal standing on its hind legs and having the paws of its forelegs of greatly enlarged size and grotesque appearance.

The torso of the figure may be provided 20 with advertising matter directing the attention to the goods displayed from the rack-like extremities.

The invention is carried out by the provision of greatly enlarged fingers or claws which are jointed to a grotesque simulation of 25 a wrist and the wrist, in turn, is jointed to an articulated system of pieces serving as the arms or forelegs of the figure. A suitable covering to represent the dress of a human being, or the body of an animal, is provided to 30 cover up the articulated system of parts but to leave exposed the greatly enlarged hands or paws.

The joints connecting the fingers to the wrist part of the figure can be varied and so 35 may the type of joint between the wrist parts and the simulated arm or foreleg parts, and other changes be resorted to without departing from the essential features of the invention, a practical embodiment of which is 40 shown in the accompanying drawings in which:

Figure 1, is a front elevation showing the improvements in connection with the figure of a man who is in standing position;

Fig. 2, is a detail view of the improvements by themselves; and

Fig. 3, is a detail view of one of the fingers.

While I have illustrated the use of the invention only in connection with the use of a 50 figure of a man, it is to be understood that the

claims are intended to cover either the figure of a man, woman, child, or animal.

The figure 1 of the man which is shown in Fig. 1, may be dressed in any style and the body thereof may be of any construction preferred. Any of the well-known "models" in store windows or other places may be employed for this purpose, as my improvements relate to the hands and arms of the figure, if it be that of a human being, or, the forelegs and paws of the animal if the figure be that of an animal.

The parts which represent the hands comprise a cross-piece 2 representing the wrist, and rods or flat pieces or strips 3 representing the fingers. These may be suitably painted or treated to simulate the knuckles, nails, and general appearance of fingers. The fingers are pivoted at 4 to the wrist 2, such pivots being rivets but other pivots may be used.

The arms which are covered by the coat sleeves 5, comprise upper arm sections 6, lower arm sections 7, and any suitable hinge or joint 8 connecting said sections so that they are articulated to permit bending as 75 may be desired. The sections 7 are jointed at 9 to the wrist parts 2. Ordinarily, hinged joints may be used but I prefer to provide ball and socket joints so that the hands may be moved to any desired position, upwardly, 80 downwardly, or laterally. The ball and socket joint permits many grotesque individual, and relative, positions of the hands to enhance the striking appearance of the figure.

The sections are hinged at 10 to the frame or back piece 11 of the body of the figure.

The front of the figure may be provided with signs 12 directing attention to the advertiser and the goods he is displaying. Any 90 suitable placards may be used for that purpose, or, the body of the figure may have a special sign holder.

I have illustrated men's socks at 13 to show how goods may be suspended from the fingers 95 3, said fingers constituting racks for the display of any merchandise susceptible of hanging from said fingers.

When my improvements are provided in connection with a figure of an animal, the 100

equivalent of the fingers 3 will be the paws or claws or the forelegs of the animal and said forelegs will comprise parts similar to the parts 6, 7, 2, and 9, which have been described.

5. What I claim is:

In an adjustable stand, the combination with a frame or back piece adapted for connection to any suitable supporting means therefor, of a pair of arms, each arm comprising a plurality of sections hinged or jointed together to enable the respective sections to assume different angular relationships to each other, one end section of each of said pairs of arms being hinged or jointed to the frame or back piece at different points thereof, thereby enabling the sectional arms to be moved as a unit toward or away from each other aside from the adaptability of the sections thereof to assume different angular positions in relation to each other, independent cross pieces, each having a universal joint connection to the remaining end section of the arms to enable said cross pieces to assume any angular position in relation to said arms, and a group of strips carried by each cross piece, the respective strips being independently pivoted in the same general plane to the cross piece which carries it, in side by side relationship, enabling the strips to be made to assume different spread or contracted positions in relation to each other irrespective of the angular position of the cross piece or of the arm which carries said cross piece.

35. In testimony whereof I affix my signature.
